CLAIM

The ornamental design for a beverage container with lid, as shown and described.

DESCRIPTION

FIG. 1 shows a top perspective view of the new design for a beverage container with lid.

FIG. 2 shows a bottom perspective view of the beverage container with lid.

FIG. 3 shows a front elevational view of the beverage container with lid.

FIG. 4 shows a top view of the beverage container with lid; and,

FIG. 5 shows a bottom view of the beverage container with lid.

A rear elevational view, a right side elevational view and a left side elevational view of the beverage container with lid are each the same as the front elevational view of the beverage container with lid.

1 Claim, 4 Drawing Sheets
